BAG OPENING AND SPREADING MECHANISM

Victor George Williams, Toronto, Ontario, Canada, assignor, by mesne assignments, to Delamere & Williams Company, Limited, Toronto, Ontario, Canada

Application July 13, 1948, Serial No. 38,377

5 Claims. (Cl. 226—49)

1.

The invention relates to new and useful improvements in apparatus for automatically packaging commodities in bags and has particular reference to the means for opening and spreading the bags preparatory to the filling or charging thereof.

The bag particularly contemplated by the invention is a tubular structure to which spaced axial creases impart a generally rectangular perimeter. There are thereby formed therein two parallel wider sides, hereinafter referred to as panels, joined by narrow sides or gussets. In the conventional flat-folded or collapsed form in which it is delivered by the bag manufacturer, the gussets are tucked between the panels which are then turned up and cemented in the usual manner to form a bottom closure, the remaining open end being the mouth of the bag. Upon expansion to full commercial capacity, the closed end of the bag is to be spread into a flat bottom with a rectangular outline corresponding dimensionally to the measurements at the bag mouth.

The actual spreading of a bag is normally preceded by the step of preliminarily opening it to admit the spreading mechanism. Past opening means have proven too forcible for the bags, particularly at higher operational speeds, whereby many bags were torn and the entire process thus resultantly delayed and disturbed. This situation necessitated that the machines be run slowly which, understandably, had a markedly adverse effect on the economy of the entire bagging process.

It is therefore the broad object of the invention to provide a safe means, associable with the forming part of a bagging machine of the character contemplated, for opening and spreading bags and delivering them to a suitable conveying mechanism at higher speeds than has heretofore been customary.

It is also an important object of the invention to provide new and improved means for preliminarily opening the bags under consideration.

It is a further object of the invention to provide means for flattening or squaring the bottom of a bag of the character described.

It is a still further object of the invention to provide means for operating upon the side gussets of the said bag, particularly but not exclusively adjacent the bottom, where they are caught between the panels, in such wise as to preclude the tendency thereof to return the bag to its original collapsed condition.

Other objects of the invention, more or less,

broad than those hereinbefore described will appear from the following description of the elements, parts and principles constituting the invention which is illustrated in the annexed drawings of a preferred embodiment thereof, by way of example only, wherein:

Fig. 1 is a side elevational view of the invention partly sectioned to expose some of the parts.

Fig. 2—a view similar to Fig. 1 at a stage in the operation thereof.

Fig. 3—a side elevational view partly in section of a detail of the invention at a further operational stage.

Fig. 4—a perspective view partially cut away showing the side, front and rear of a partially opened bag as contemplated by the invention.

Fig. 5—a view similar to Fig. 4 wherein the bag is fully expanded.

Fig. 6—a front elevational view of a part of the bag expanding mechanism.

Fig. 7—a perspective view of the side and front of the invention.

Figs. 8, 9 and 10—a sectional view of the parts shown in Fig. 6 at various stages in the operation thereof.

Fig. 11—a front elevational view of the invention, and

Figs. 12 and 13—front elevational views of a modification of the bottom forming mechanism appearing in Figs. 8 to 10.

Like reference numerals refer to like parts of the invention throughout the enumerated views.

The bag, contemplated by this preferred embodiment of the invention comprises a front panel 2, a somewhat higher back panel 3 terminating in the conventional flap 4, gussets 5—5 linking the panels 2 and 3 and a bottom 6, substantially as will appear from Figs. 4 and 5 of the drawings. It is noteworthy that in the construction of the present bag, the gussets 5—5 are cemented in folded position to the bottom 6 of the bag.

Since neither the bag filling nor the sealing mechanism with which the instant invention is intended to be associated, form part hereof, only such portions thereof as cooperate with the present apparatus will be illustrated in the drawings and referred to herein. One such part is the conveyor 8 which is arranged ahead of and in bag receiving relation to the bag opening and spreading means to be described and which is adapted to convey expanded bags 1 to the filling mechanism (not shown). The conveyor 8 includes a series of bag receiving sockets 9 over-

Another such part is the eccentric means for delivering reciprocating power from the driving mechanism of the packaging machine to the instant apparatus, the said eccentric means consisting of a crank member 11 mounted on rotating shaft S and associated with pitman 12. The reference letter "F" is generally applied to the packaging machine frame and/or to various portions thereof.

One of the broad objects of the invention is achieved by restrainingly poised a movable panel engaging element above the bag 1. Resilient bag-entering tension is constantly maintained thereon which, when the restraint is removed, moves the said element only so far as will enable it to operate on the bag 1 without damaging it, irrespective of the speed at which the process is performed.

It should be noted that herein, the term "opening" is restricted in application to the bag mouth only while the other more comprehensive terms, "spreading" or "expansion," refer to the entire bag 1.

The instant apparatus includes a ram 15 which is reciprocable in a channelled ram guide 16 carried by the frame F of the packaging machine. From its upper portion projects a wrist pin 17 to which the pitman 12 is suitably connected. Enclosing the ram 15 in its guide 16 is the cover plate 18 which is secured to the said ram guide 16 either directly or, as may be necessitated by the size of the ram 15, through shims 19, and has a median slot 20 for the wrist pin 17. Beyond the lower end of the ram guide 16, the cover plate 18, still slotted, is inclined away therefrom terminating in a boss 21 housing a through-going, headed, spring controlled bumper 23.

Also suitably secured to the frame F is an open ended magazine 25 for a stack 26 of bags 1 which is equipped with conventional stack advancing means such as spring 24. A stop 27 is fixed to the frame F at the delivery end of the magazine 25 tapering to a chisel-pointed offset claw 28 which is so positioned relative to the magazine 25 that it is adapted to engage the top flap 4 of the bag 1 leading the stack 26 thereof. Moreover, its position is also such that it extends to but does not intersect the path of the ram 15 for reasons which will duly appear. Air passages 29 therein from an air hose connecting nipple 30 are adapted to conduct and discharge air, whether continuously or intermittently, through the offset claw 28 of the stop 27. When so discharged, the air tends to puff open the mouth of the leading bag 1. It should be observed that the pressure of the spring 24 on the stack 26 is communicated therethrough and causes, in effect, the flap 4 to be grasped by stop 27.

The means for completing the preliminary opening of the bag 1 includes a hair-pin shackle 34 saddled over the wrist pin 17 between pitman 12 and ram guide cover plate 18 and terminating in bushings 35-35 accommodating trunnions 36-36 trammed in slots 37-37 formed in walls 38-38 projecting from juxtaposed angle brackets 39-39 secured to the said cover plate 18. The said trunnions 36-36 extend from one end of a finger 40 which, passing through and playing in the cover plate slot 20, is adapted to reach to and contact the offset claw 28 of the stop 27, being poised for entry into the leading bag 1. By referring particularly to Figs. 1, 2 and 3 of the drawings, it will be seen that when so disposed the intermediate portion of the said finger 40 thus intersects the path of the ram 15.

A tension spring 41 anchored to the boss 21 is connected to the finger 40 in such wise as to urge the free end thereof against the stop 27, which said free end is somewhat offset and chisel pointed and is hereinafter referred to as its claw 44. It is noteworthy that the said tension spring 41 also applies a downward pull to the finger 40 urging its entry into the bag 1 but that such movement is restrained or counteracted by the shackle 34 when it is raised by ram 15 through the intermedium of wrist pin 17.

Thus as ram 15 and wrist pin 17 begin their descent, and thereby remove the restraint on the wrist pin saddling shackle 34, the tension spring 41 is permitted to pull the finger trunnions 36-36 down in the angle bracket slots 37-37 whereby the co-moving finger claw 44 slides down the stop 27 into the bag 1 in front panel 2 engaging position; the said slots 37-37 limiting the depth of penetration thereinto and hence precluding injury to the bag 1 irrespective of the speed at which the entry is effected.

Continuing its movement to its next ensuing position with the wrist pin 17 travelling inside shackle 34, the ram 15 then intervenes between the stop 27 and the finger 40, diverting the latter with the front panel 2 towards the bumper 23 between which two elements the said front panel 2 is grasped.

The mouth of the bag 1 being thus fully opened, the ram 15 assumes its next position in the bag 1. It should have been stated that the cross-sectional measurements of the ram 15, as contemplated by the present embodiment of the invention, are slightly less than the corresponding interior measurements of the bag 1 when it is fully expanded. Thus on entering therein the ram 15 tends to spread the bag 1 to near-maximum capacity. On contacting its bottom 6 the ram 15 then disengages the bag 1 from the respective grasps of the stop 27 on the one hand and from the finger 40 and bumper 23 on the other hand and carries it towards the conveyor 8 lying therebelow in one of whose sockets 9 it is then deposited. This being the bottom of its stroke, the ram 15 then rises, passing the finger 40 which is then restored by tension spring 41 to pre-intervention position, and re-engages shackle 34 raising it and finger 40 to the positions initially occupied thereby at the commencement of the downward stroke. This completes one up-and-down cycle of the ram 15.

As has been already said, one of the objects of the invention is to impart a flat rectangular character to the bag bottom 6 as shown particularly in Fig. 5 and identified by reference 6'. Prior to this step the bag 1 is substantially wedge-shaped (Fig. 4) with the folded gussets 5-5 caught at the bottom 6 of the bag 1. Thus, to facilitate its entry thereinto, the terminus or head 45 of the ram 15 is tapered as illustrated and is hollowed, moreover, to accommodate the bottom forming mechanism to be described.

The said mechanism includes a recessibly projecting plunger 46 having a shaft 47 and a tongue 48, the upper portions of whose sides incline towards and merge with the shaft 47, the said inclined portions being hereinafter termed the slopes 49-49. The plunger 46 is movable axially of the ram 15, its shaft 47 being fitted with a compression spring 50 and slidably engaged in a bearing 51 suitably disposed in and forming an integral part of the head 45. Fastening means, such as nut 47', serves to retain the shaft 47 in 75 the bearing 51 which latter element also forms

one abutment for the compression spring 50, the other being shoulder 50' on shaft 47.

Flanking the plunger 46 are a pair of substantially triangular spreaders 52—52 each whereof is expellably suspended by its apex inside the head 45, being adapted to be expelled therefrom through a slot 53 in the side of the said head 45. One side or facet 54 of each spreader 52 is adapted to abut a plunger slope 49 through whose interaction the said spreader 52 is pressed outwardly or expelled from the head 45 as the plunger 46 is pushed back thereinto. One or more pull springs 55 interconnect the spreaders 52—52, through suitable media, whereby they are retractable back into the said head 45 as the counter pressure thereon is abated.

It will now be apparent that when the ram 15 enters the bag 1 and carries it to the socket 9 on the conveyor 8 in the manner hereinbefore described, the plunger tongue 43 will strike the socket bed 19 and be thus recessed into the ram head 45 expelling the spreaders 52—52 and forcing them against the bag gussets 5—5. These latter members being cemented in tucked-in position as aforesaid, the effect of the spreaders 52—52 thereon is to form a new transverse crease 5' in each thereof adjacent the new bottom 6' thus causing or at least assisting the gussets 5—5 to assume a desirable perpendicularity.

The thickness of the head 45 being substantially equal to the corresponding dimension of the bag 1, it is adapted to crease the panels 2 and 3 accordingly, which effect combines with the new gusset creases 5'—5' to completely reshape or square the bag bottom 6 of Fig. 4 to the form denoted by reference 6' in Fig. 5.

According to the nature of the bag material, the effect of the new gusset creases 5'—5' may be found inadequate to completely perpendicularize the gussets 5—5 whereby to maintain the mouth of the bag 1 as fully open as is necessary, for filling purposes for example. To obviate this contingency it has proven efficacious to form a second transverse crease or dent 60 slightly below the top edge of each gusset 5.

For this purpose there is provided a rib 61 at suitable bag-entering level on each side 15' of the ram 15, and a ram contacting roller 62 formed of, or at least rimmed with, rubber or other comparable resilient substance, mounted on the frame F.

Thus while the ram 15 is carrying the bag 1 to the conveyor 8, the rib 61 will pass the roller 62, pressing thereinto through the bag material to form the dent 60.

It will be seen that each roller 62 has the additional advantageous faculty of ironing out its associated gusset 5 against the ram 15 whereby to further stiffen it.

It need hardly be pointed out that when the ram 15 is raised to complete the cycle, the compression spring 51 will again eject the plunger tongue 43 thus enabling the pull spring 55 to retract the spreaders 52—52 to pre-expulsion position.

In Figs. 12 and 13 of the drawings appears a modification of the bottom forming mechanism hereinbefore described and illustrated in Figs. 8, 9 and 10; the principal object of the modification being to do away with pull springs 55.

Each new spreader 70 is more or less bell-crank-shaped terminating at its top in a tail piece 71, besides having other properties, such as facet 72, in common with its prototype spreader 52. The new plunger 73 also corresponds to its counter-

part plunger 46 in that it has a tongue 74 and slopes 75—75 adapted to co-operate with facets 72—72 of the new spreaders 70—70. Herein, however, the plunger head 76 has another pair of slopes or cam surfaces 77—77 whereof each is adapted to act on a tail piece 71.

The arrangement of the parts is such that the inward movement of the plunger 73 expels each spreader 70 through the interaction of facet 72 and slope 75. Subsequently, when the plunger 73 is again projected through the ram head 45, each cam surface 77 acts on a tail piece 71 to restore the spreader 70 to pre-expulsion position.

Herein, also, the tongue 74 has a slot 80 in which fits fixed guide pin 81, the object whereof is to maintain the co-axial relationship of the plunger 73 and the ram 15.

The instant embodiment of the invention has been thoroughly tested, and found eminently satisfactory, and has hence been selected for illustrative purposes. However, it is well understood that many structural changes can be made in the apparatus herein described which may make for equal or lesser efficiency. These, together with certain structural details which are common to the art, having been omitted herefrom for the sake of simplicity and clarity, it is not to be construed that such omission constitutes an abandonment of any of the forms of the invention which falls within the purview of the following claims.

What I claim as my invention is:

1. Opening means for a bag having opposed panels comprising, a fixed stop element adapted to engage the inner face of one of said panels as a bag is fed laterally thereto, means for feeding and guiding bags to said stop, a pivotally supported finger having its free end adjacent said stop element and directed generally inwardly of said bag, the pivotal support for said finger being mounted for limited sliding movement relative to said stop in a direction to project said finger inwardly of said bag between said panels, spring means urging said pivotal support in said direction, and a member movable from a retracted position to a position in said bag between said stop and said finger to thereby swing said finger about its pivot and move said panels apart, said movable member having a portion movable therewith and connected to said pivotal support by a lost-motion means to hold said finger out of said bag against the action of said spring while said movable member is in said retracted position.

55 2. A device as defined in claim 1 including stop means limiting projecting movement of said pivotal support.

3. Mechanism for opening a bag having opposed flexible panels joined by longitudinally folded gussets comprising, means including a ram mounted for reciprocatory movement into and out of said bag to separate the said panels and thus open the bag, ribs carried by said ram adjacent the inner surfaces of said gussets and extending transverse to the direction of ram movement, and resiliently distortable means positioned closely adjacent the outer faces of said gussets and the path of movement of said ribs whereby movement of said ram into said bag causes said ribs to press said gussets against and into said resilient means and impress in said gussets a crease transverse to said longitudinal fold.

70 4. Mechanism for opening a bag having opposed panels joined by a longitudinally folded

gusset comprising, means including a ram mounted for reciprocatory movement to move one end thereof into and out of said bag to separate the said panels and thus open the bag, said ram having a transverse opening adjacent said end, a movable element movable to a position where it is wholly contained within said opening, means normally holding said element within said opening, and means responsive to movement of the ram to the bottom of said bag for moving said element outwardly of said opening to engage and expand said folded gusset, said element having a gusset engaging portion movable therewith along a transverse path closely adjacent the plane of the end of said ram.

5. A device as defined in claim 4 wherein said ram movement responsive means includes an actuator in said ram and having a part normally projecting from the end of the ram, said actuator being moveable to retract said part into said ram, and inter engaging means between said actuator and moveable element.

VICTOR GEORGE WILLIAMS.
